ADJUSTABLE GOLF CLUB

Joseph Verderber, Cleveland, Ohio

Original application September 5, 1945, Serial No. 614,461. Divided and this application November 18, 1948, Serial No. 60,700.

4 Claims. (Cl. 273—79)

1

This invention relates generally to golf clubs, but has reference more particularly to golf clubs having angularly adjustable heads and to means for adjusting said heads. This application is a division of my copending application, Serial No. 614,461, filed September 5, 1945, now Patent No. 2,455,150, for an improvement in golf clubs.

The present invention has as its primary object the provision of improved means for locking the head of the club in adjusted position, such means including coacting serrations or teeth on the shank and head which extend over a substantial area of the shank and head.

Another object of the invention is to provide means for locking the head and shank together, which means is characterized by a minimum number of easily manufactured parts, and which is devoid of sliding or loose parts or elements which are likely to become lost or create noise or vibration.

A further object of the invention is to provide a golf club of the character described, in which the locking means or elements are readily engaged or disengaged upon only a slight relative movement between the head and shank.

Other objects and advantages of my invention will be apparent during the course of the following description.

In the accompanying drawings forming a part of this specification, and in which like numerals are employed to designate like parts throughout the same:

Fig. 1 is a longitudinal cross-sectional view of a golf club embodying the features of my invention, certain parts thereof being shown in elevation.

Fig. 2 is a fragmentary cross-sectional view, taken on line 2—2 of Fig. 1.

Fig. 3 is a side elevational view of one of the head locking members shown in Fig. 1.

Fig. 4 is a view similar to Fig. 1, but showing a modified form of the invention.

Fig. 5 is a cross-sectional view taken on line 5—5 of Fig. 4, but with the head locking member removed for clarity.

Fig. 6 is a cross-sectional view of the head locking member shown in Fig. 4.

Referring now particularly to Figs. 1—3 of the drawings, it will be seen that the golf club includes a head 92 having a bore 122 extending therethrough. The head 92 is mounted on the shank portion 80 of a hosel 123 which, in turn, is secured to a shaft (not shown). The shank 80 of the club is formed to provide a reduced portion 81, a portion 82 of square cross-section, a round portion 83, a second portion 84 of square

cross-section and an end portion 85 which is threaded. The junction of the portions 81 and 82 forms a stop shoulder 86, and the junction of the portions 83 and 84 forms a stop shoulder 87.

Mounted on the portion 82 of the shank 80, and bearing against the stop 86, is a frustoconical shaped head locking member 88 having splines or serrations 89 extending along its tapered outer surface. The splines 89 are normally in mesh or interlocked engagement with splines or serrations 90 on the inner face of a member 91 which may be formed as an integral part of the head 92 or, preferably, may be keyed or otherwise rigidly secured to the head within the bore 122.

Mounted on the portion 84 of the shank 80, and bearing against the stop 87, is a frustoconical head locking member 93 which is similar to the member 88 and has splines or serrations 94 formed thereon. The splines 94 are normally in mesh or interlocked engagement with splines or serrations 95 on the inner face of a member 96, which, in this case, is rigidly secured to the head 92 by means of a set screw 97. It will be understood, however, that the member 96, under certain conditions, may be formed integrally with the head 92.

The member 93 is secured against axial displacement from the shank by means of a nut 98 which is threadedly secured to the portion 85 of the shank 80.

A washer 99 is mounted on the portion 83 of the shank and is normally in abutment with one end of the member 96, being retained in such abutment by means of a compression coil spring 100, which is mounted on the portion 83 of the shank, between the washer 99 and one end of the member 88.

In Fig. 1 the head is shown in locked engagement with the shank 80, due to the interlocked engagement of the members 88 and 93 with the members 91 and 96, respectively.

When it is desired to change or adjust the angularity of the head 92 relatively to shank 80, it is only necessary to push the head to the right from the position shown in Fig. 1. This causes the member 96 to move out of locked engagement with the member 93, and the member 91 to move out of locked engagement with the member 88 and at the same time the washer 99 causes the spring 100 to be compressed. Thereafter the head may be rotated to any desired position of relative angularity and then released, thereby permitting the spring 100 to return the head to its locked position.

In the modified form of my invention, shown in

Figs. 4-6 of the drawings, the shank portion 101 of the hosel 125 is similarly contained within the bore 124 of a club head 113. The shank 101 is formed to provide a reduced portion 102, a portion 103 of square cross-section, a round portion 104, a second portion 105 of square cross-section, and an end portion 106 which is threaded. The junction of the portions 102 and 103 forms a stop shoulder 107, and the junction of the portions 104 and 105 forms a stop shoulder 108.

Mounted on the portion 103 of the shank 101 and bearing against the stop 107 is a frustoconical shaped head-locking member 109 having splines or serrations 110 extending along its tapered outer surface. The splines or serrations are normally in mesh or interlocked engagement with splines or serrations 111 on the inner face of a member 112, which may be formed as an integral part of the head 113 or may be keyed or otherwise rigidly secured to the head.

Mounted on the portion 105 of the shank 101 and bearing against the stop 108, is a frustoconical head-locking member 114 which is similar to the member 109 and has splines or serrations 115. The splines 115 are normally in mesh or interlocked engagement with splines or serrations 116 formed on the inner face of a member 117 which, in this case, is rigidly secured to the head 113 by means of a set screw 118, but which, under certain conditions, may be formed integrally with the head 113.

The member 114 is secured against axial displacement from the shank 101 by means of a nut 119 which is threadedly secured to the portion 106 of the shank.

A washer 120 is mounted on the portion 104 of the shank and is normally maintained in abutment with one end of the member 112, being retained in such abutment by means of a compression coil spring 121. The spring 121 is mounted on the portion 104 of the shank between the washer 120 and one end of the member 114.

In Fig. 4, the head 113 is shown in locked engagement with the shank 101 due to the interlocked engagement of the members 109 and 114 with the members 112 and 117 respectively, it being noted that all of these members are in a position which is the reverse of the position of the corresponding members in the embodiment disclosed in Fig. 1.

When it is desired to change or adjust the angularity of the head relatively to the shaft, it is only necessary to pull the club head 113 to the left from the position shown in Fig. 4. This causes the members 112 and 117 to move out of locked engagement with the members 109 and 114 respectively, and at the same time, the washer 120 causes the spring 121 to be compressed. Thereafter, the head may be rotated to any desired position of relative angularity and released, whereupon the spring 121 will return the head to its locked position.

Although, in the normal swing of the club, there is a slight centrifugal effect tending to urge the club head 113 in a direction away from the hosel 125, the spring 121 is of sufficient strength to overcome this tendency and no unauthorized unlocking of the club head will occur. In the embodiment shown in Fig. 1, the unlocking movement is, of course, in a direction toward the hosel 123 and the effect of the slight centrifugal force

on the head 92 when the club is swung would tend to increase the effectiveness of the interlocking action.

It will thus be apparent that I have provided an adjustable golf club head consisting of a minimum number of easily manufactured parts which is readily engaged or disengaged upon a very slight relative movement between the head and the shank.

It is to be understood that the forms of my invention, herein shown and described, are to be taken as preferred examples of the same, and that various changes in the shape, size and arrangement of the parts may be resorted to without departing from the spirit of my invention or the scope of the subjoined claims.

Having thus described my invention, I claim:

1. An adjustable golf club comprising a shaft, a shank extending angularly therefrom, a head mounted slidably on said shank, said head having longitudinally spaced axially extending convergent serrations provided circumferentially internally thereof, a pair of conical locking members having external circumferential serrations secured to said shank in longitudinally spaced relationship coextensive with said serrations on said head and parallel thereto, and a compression spring mounted on said shank and having one end thereof seated against one of said members and the other end thereof abutting said head whereby to yieldably maintain the serrations on said head in nested interlocked engagement with the serrations on said shank at selected positions of angularity of said head relatively to said shank.

2. A golf club comprising a shaft, a shank extending therefrom, a head slidably mounted on said shank, a conical serrated locking member removably secured to said shank, a second conical serrated locking member mounted on said shank in longitudinally spaced relationship to said first locking member, locking elements having serrated conical inner surfaces complementary to said locking members secured to said head, and spring means abutting one of said members and engaging said head to urge said locking elements into interlocking engagement with said locking members, the taper on said members being in a direction to limit movement of said head away from said shaft.

3. A golf club as defined in claim 2 wherein said spring means is disposed intermediate said locking members.

4. A golf club as defined in claim 2 wherein said locking elements are removably secured to said head.

JOSEPH VERDERBER.
